UNITED STATES PATENT OFFICE.

GARTH G. GILPIN, OF RIVERSIDE, ILLINOIS, ASSIGNOR TO P. H. MURPHY COMPANY, OF NEW KENSINGTON, PENNSYLVANIA, A CORPORATION OF PENNSYLVANIA.

CAR ROOF.

Application filed March 25, 1921. Serial No. 455,499.

To all whom it may concern:

Be it known that I, GARTH G. GILPIN, a citizen of the United States, residing at Riverside, in the county of Cook and State of Illinois, have invented new and useful Improvements in Car Roofs, of which the following is a specification.

This invention relates to improvements in railway cars and more particularly to the roofs for freight cars of the type generally known as all metal roofs.

It is the object of this invention to provide an all metal roof formed of roof sheets extending from side to side, rigidly secured 15 to the car frame and to each other which will be of light weight material and will afford a maximum head room or clearance on the inside of the car.

One particular advantage of this construction is that while the carlines, roof sheets and seam caps are secured together by rivets, should the rivets become loose or the heads sheared in service, water will not readily drain into the car as all of the rivet holes 25 over the car body are in a horizontal plane.

While the preferred form of this invention is illustrated upon the accompanying sheets of drawings yet minor detail changes may be made without departing from the 30 scope thereof.

In the drawings:

Figure 1 is a top plan view of a portion of a car roof embodying this invention, with parts broken away.

35 Figure 2 is a view in vertical section, taken on the line 2—2 of Figure 1, looking in the direction of the arrows.

Figure 3 is a view in side elevation of Figure 1 with parts broken away.

40 Figure 4 is a view in section taken on the line 4—4 of Figure 2.

Figure 5 is a view in section taken on the line 5—5 of Figure 2.

45 Figures 6 and 7 are views similar to Figures 4 and 5, of a modified form of construction.

Figure 8 is a view in side elevation of the running board saddle shown in Figure 6.

50 The embodiment of this invention as illustrated comprises a plurality of roof sheets 1, extending from side to side of the car with their eaves ends resting upon and bent over the outer edge of the side plates 2, and rigidly secured to the side plates, preferably 55 by rivets as shown. The adjacent edges of

the sheets are provided with continuous up-standing flanges 3 and are spaced apart a sufficient distance to receive between them an inverted U-shaped metal carline 4. The sides of these carlines are of uniform height 60 throughout and their lower edges are bent outwards from each other forming flanges 5 which are at right angles to the sides. The carlines extend from eaves to eaves with their ends resting upon the upper surface of 65 the side plates extending therebeyond and bent downward, as shown. The bodies and the adjacent edges of roof sheets are supported upon the flanges 5 of the carlines with the flanges 3 of the roof sheets engag- 70 ing the parallel sides of the carlines for preferably about half the height of the carline. To provide a water-tight closure and give additional rigidity to the seams, seam caps 6 of inverted U-shape are applied over 75 the carlines having out turned flanges 7 at the bottom of the sides, which rest upon the body of the roof sheets and hold the roof sheet flanges in engagement with the side walls of the carlines. These seam caps are 80 preferably pressed from a rectangular sheet of metal and extend from side to side resting at their eaves ends upon the roof sheets over the side plates and extending therebeyond and bent down over the tops of the car- 85 lines and terminated therewith, as shown.

The seam caps are of greater height than the carline at the ridge and are gradually reduced in height as they approach the eaves, until the tops of the caps engage the tops of 90 the carlines over the side plates, the flanges from the side walls of the caps increase in width in proportion to the decrease in height of the caps, thereby not only utilizing the surplus metal formed in decreasing the 95 height but also adding additional strength to the cap. The caps are preferably secured to the carlines and thereby securing the roof sheets by a plurality of rivets 8 between the ridge and eaves which passes in a horizontal 100 direction through the carline and cap above the roof sheet flange and at the eaves by rivets 9 passing through the side plate, roof sheets and out turned flanges of the caps.

Figures 5 and 6 illustrate a modification 105 in which the out turned flanges 5 of the carlines are provided with a continuous crimp or corrugation 10, the body of the roof sheets having a similar corrugation or crimp 11 to rest thereon and the out turned 110

flanges 7 of the caps are provided with a like corrugation or crimp 12, to provide a more perfect joint between the three parts and prevent the edges of the roof sheets 5 from pulling out between the carlines and caps. If desired the cap side walls may have an offset 13, to accommodate the roof sheet flanges and allow the side walls to snugly fit the side walls of the carlines.

- 10 In this type of roof it is preferable to support the running boards 14 by saddles in the form of plates 15 having a portion riveted to the top of the seam cap with a portion 16 extending down over the side 15 of the cap and secured thereto by the rivets securing the cap to the carline and a portion 17 on the other side stuck up and extending beyond the cap to support the underside of the running board above the 20 rivets on the top of the cap and to which portion the running boards may be bolted as shown in Figures 1, 2 and 4.

Another form of running board saddle is illustrated in Figures 6 and 8 which comprises a plate 18 of inverted U-shape, whose side walls are shouldered to rest upon the top of the seam cap and are secured to the side walls of the caps by horizontal rivets above the top of the carline. The running 30 boards rest upon the top of the saddles and are preferably bolted thereto as shown in Figure 6. The side walls of the saddle being cut away, as at 19, on each side for the application of a wrench for operating the 35 nut on the bolt as shown in Figure 8.

Another advantage of this construction is that the caps are not required to be riveted throughout their entire length to the carline to form a rigid structure. The caps 40 and roof sheets are riveted to the side plates, with the caps in contact with the carlines and closely holding the said flanges between them, and it is only necessary to rivet the caps and carlines for about one- 45 half the distance from the ridge to the eaves. The rivet holes over the body of the car are in a horizontal plane and therefore do not afford a ready access for water draining into the interior of the car.

50 The form of carlines extending over the side plates provides a means for ventilation and the down turned ends act as baffles to the entrance of rain or water. As all metal roofs will sweat when there is a difference 55 in temperature between the interior and exterior of the car this form of ventilation tends to maintain an equal temperature on both sides of the roof sheets.

What I claim is:

- 60 1. In an all metal car roof, roof sheets having their eaves ends secured to the car side plates and having upstanding flanges on their adjacent meeting edges, inverted U-shaped carlines extending from side to side therebetween having outstanding flanges 65

on their side walls resting upon and secured to the car side plates, inverted U-shaped seam caps having outstanding flanges on their side walls engaging and holding the roof sheets and roof sheet flanges against the carline flanges and side walls, and means securing the seam caps to the carlines. 70

2. In an all metal car roof, roof sheets having their eaves ends secured to the car side plates and having upstanding flanges 75 on their adjacent meeting edges, inverted U-shaped carlines extending from side to side therebetween having outstanding flanges on their side walls resting upon and secured to the car side plates, and inverted U-shaped seam caps having outstanding flanges on their side walls, engaging and holding the roof sheets and roof sheet flanges against the carline flanges and side walls, and means 80 securing the seam caps to the carlines, comprising rivets passing in a horizontal direction through the side walls of the carlines 85 and caps.

3. In an all metal car roof, roof sheets having their eaves ends secured to the car side plates and having upstanding flanges 90 on their adjacent meeting edges, inverted U-shaped carlines extending from side to side therebetween having outstanding flanges on their side walls resting upon and secured to the car side plates, inverted U-shaped seam caps having outstanding flanges on their side walls increasing in width from ridge to eaves, said caps engaging and holding the roof sheets and roof sheet flanges against the carline flanges and side walls, and means 95 securing the seam caps to the carlines. 100

4. In an all metal car roof, roof sheets having their eaves ends secured to the car side plates and having upstanding flanges on their adjacent meeting edges, inverted U-shaped carlines extending from side to side therebetween having outstanding flanges on their side walls resting upon and secured to the car side plates, inverted U-shaped seam caps having outstanding flanges on their side walls, engaging and holding the roof sheets and roof sheet flanges against the carline flanges and side walls, 105 means securing the seam caps to the carlines, and means securing the seam caps to the car side plates. 110

5. In an all metal car roof, roof sheets having their eaves ends secured to the car side plates and having upstanding flanges on their adjacent meeting edges, inverted U-shaped carlines extending from side to side therebetween having outstanding flanges on their side walls resting upon and secured to the car side plates, inverted U-shaped seam caps having outstanding flanges on their side walls, engaging and holding the roof sheets and roof sheet flanges against the carline flanges and side walls, said caps 120 being of greater height than the carlines 125 130

at the ridge and decreasing constantly in height towards the eaves and means securing the seam caps to the carlines.

6. In an all metal car roof, roof sheets having their eaves ends secured to the car side plates and having upstanding flanges on their adjacent meeting edges, inverted U-shaped carlines extending from side to side of uniform height therebetween having outstanding flanges on their side walls resting upon and secured to the car side plates, inverted U-shaped seam caps having outstanding flanges on their side walls engaging and holding the roof sheets and roof sheet flanges against the carline flanges and side walls, said caps being of greater height than the carlines at the ridge and decreasing in height towards the eaves to engage the top of the carlines and means for securing the seam caps to the carlines.

7. In an all metal car roof, roof sheets having their eaves ends secured to the car side plates and having upstanding flanges on their adjacent meeting edges, inverted U-shaped carlines extending from side to side therebetween having outstanding flanges on their side walls resting upon and secured to the car side plates, inverted U-shaped seam caps having outstanding flanges on their side walls engaging and holding the roof sheets and roof sheet flanges against the carline flanges and side walls, means securing the seam caps to the carlines comprising rivets passing in a horizontal direction through the side walls of the carlines and caps, and means securing the seam caps to the car side plates comprising rivets passing through the seam cap flanges, roof sheets and side plates.

8. In an all metal car roof, roof sheets having their eaves ends secured to the car side plates and having upstanding flanges on their adjacent meeting edges, inverted U-shaped carlines extending from side to side therebetween having upstanding flanges on their side walls resting upon and secured to the car side plates, inverted U-shaped seam caps having outstanding flanges on their side walls engaging and holding the roof sheets and roof sheet flanges against the carline flanges and side walls, said caps being of greater height than the carlines at the ridge and decreasing constantly in height towards the eaves, and means for securing the seam caps to the carlines comprising rivets passing in horizontal direction through the side walls of the carlines and caps.

9. In an all metal car roof, roof sheets having the eaves ends secured to the car side plates and having upstanding flanges on their adjacent meeting edges, inverted U-shaped carlines extending from side to side of constant height therebetween having outstanding flanges on their side walls rest-

ing upon and secured to the car side plates, inverted U-shaped seam caps having outstanding flanges on their side walls increasing in width from ridge to eaves, said caps engaging and holding the roof sheets and roof sheet flanges against the carline flanges and side walls, said caps being of greater height than the carline at the ridge and decreasing constantly in height towards the eaves to engage the top of the carlines, means securing the seam caps to the carlines comprising rivets passing in a horizontal direction through the side walls of the carlines and caps, and means securing the seam caps to the car side plates comprising rivets passing through the caps, flanges, roof sheets and side plates.

10. In an all metal car roof, roof sheets having the eaves ends secured to the car side plates and having upstanding flanges on their adjacent meeting edges, inverted U-shaped carlines extending from side to side of constant height therebetween having outstanding flanges on their side walls resting upon and secured to the car side plates, inverted U-shaped seam caps having outstanding flanges on their side walls increasing in width from ridge to eaves, said caps engaging and holding the roof sheets and roof sheet flanges against the carline flanges and side walls, said caps being of greater height than the carlines at the ridge and decreasing constantly in height towards the eaves to engage the top of the carlines, means securing the seam caps to the carlines comprising rivets passing in a horizontal direction through the side walls of the carlines and caps above the roof sheet flanges, and means securing the seam caps to the car side plates comprising rivets passing through the caps, flanges, roof sheets and side plates.

11. In an all metal car roof, roof sheets having their eaves ends secured to the car side plates and having upstanding flanges on their adjacent meeting edges, and having a continuous crimp in the body adjacent the base of said flanges, inverted U-shaped carlines therebetween having outstanding flanges on their side walls having a similar continuous crimp in said flanges, inverted U-shaped seam caps having outstanding flanges on their side walls having a similar continuous crimp therein engaging and holding the roof sheets and roof sheet flanges against the carline flanges and side walls, with the crimped portions in engagement with each other, and means securing the seam caps to the carlines.

12. In an all metal car roof, roof sheets having their eaves ends secured to the car side plates and having upstanding flanges on their adjacent meeting edges, inverted U-shaped carlines therebetween having outstanding flanges on their side walls, inverted

- U-shaped seam caps having outstanding flanges on their side walls engaging and holding the roof sheets and roof sheet flanges against the carline flanges and side walls, and means securing the seam caps to the carlines, said roof sheets, carlines and seam caps resting upon the car side plates, extending thereover and bent down therebeyond.
- 10 13. An all metal car roof comprising rectangular metallic roof sheets extending from side to side with their eaves ends adapted to rest upon and be secured to the car side plates, said ends extending therebeyond and 15 bent down thereover with the adjacent meeting edges spaced apart and provided with upstanding flanges, inverted U-shaped carlines extending from side to side of uniform height throughout having outstanding 20 flanges on their side walls arranged between the meeting edges of said roof sheets with their eaves ends adapted to rest upon the car side plates extend therebeyond and bent down thereover with their flanges supporting the body of the roof sheets and with the 25 roof sheet flanges engaging the side walls thereof for about one-half of their height, inverted U-shaped seam caps extending from side to side having outstanding flanges on their side walls arranged over the carlines and adjacent roof sheet flanges with their 30 eaves ends adapted to rest upon the roof sheets over the side plates of the car extend therebeyond and bent down thereover, said seam caps being of greater height than the 35 carlines at the ridge and decreasing in height towards the eaves with their flanges increasing in width proportionately to the decreasing height, and horizontal rivets securing the side walls of the caps and carlines above the roof sheet flanges holding the roof sheets between the side walls and flanges of the caps and carlines.

GARTH G. GILPIN.
